UNITED STATES PATENT OFFICE.

BRUNO MARTIN, OF SAGINAW, MICHIGAN.

STOVEPIPE DAMPER.

Application filed July 31, 1926. Serial No. 126,156.

This invention relates to an improvement in stove pipe dampers and ventilators of the type characterized by a section of stove pipe formed with an annular series of perforations for admission of air and a hollow truncated cone open at the top and bottom and mounted in fixed position inside the pipe, the large or lower end of the cone connected to the sides of the pipe below the perforations. These devices usually have an annular slide provided with openings corresponding to those in the pipe.

My present invention is an improvement upon the usual construction above described in that overheating of the stove pipe above the openings is prevented, because the air taken in through the openings is guided in a thin layer along the heating surface of the truncated cone and the air so admitted is mixed with the rising hot gases where they emerge from the top of the cone, the mixture taking place near the middle of the stove pipe instead of occurring as heretofore, across the entire area of the pipe.

This mixing of a central column of hot gases with a thin annular layer of heated outside air, and accomplishing the mixing in the middle of the stove pipe, improves the effectiveness of combustion. Moreover, eddies in the upwardly ascending gas current are avoided and the effectiveness of the draught is improved while increasing the rate of removal of air from the apartment in which the pipe is located.

I accomplish these results by adding to the usual perforated pipe and the hollow cone, as heretofore combined, a second hollow cone which is secured at its lower end to the interior of the pipe, above the row of perforations, so that a dead air space is formed between the stove pipe and this outer cone, and the annular heating space above referred to is formed between the two cones.

This arrangement prevents the possibility of soot, dislodged from the pipe above, coming out of the ventilating apertures of the stove pipe. The outer cone of my new combination prevents soot from reaching the openings, whereas in the arrangement heretofore employed escape of soot from the annular perforations frequently occurred.

A further novel feature of my invention is found in the inwardly curved edge or flange at the upper end of the cone. By means of this flange the gases are guided and delivered in a central stream upwardly

through the middle part of the stove pipe, and anything falling through the pipe from above, will be prevented by this flange from falling into the annular space between the cones. Such dislodged material will drop down through the centers of the two cones.

With the foregoing and certain other objects in view, which will appear later in the specification, my invention comprises the devices described and claimed and the equivalents thereof.

In the drawings, Fig. 1 is a part sectional side view of a vertically disposed length of stove pipe embodying my improvement, the space outside the usual ventilating slide being shown as communicating with a ventilating hood, which may be used for removing vapors from over cooking ranges and the like.

Fig. 2 is a perspective view of the sliding annular band that surrounds the ventilating opening of the stove pipe.

As is clearly shown in the drawings, the stove pipe damper and ventilator to which my invention is applied consists of the length of stove pipe 1 formed with an annular series of perforations 2 and provided with the internal groove 3, together with the usual truncated hollow cone 4, open at top and bottom, and provided at its lower end with a bead 5 adapted to be received in the groove 3. A band or ring 6, formed with perforations 7, is slidably mounted on the pipe 11 so as to open and close the perforations.

The structure by which I accomplish the improved results above mentioned consists in a conical member 8, open at the top and bottom, and having its bottom edge beaded as at 9. The bead is received in an internal groove 10 of pipe 1, the groove being located above the series of perforations 2 and above the band 6.

Between the cone 4 of the previous structure and the new cone 8 of my present improvement there is formed a conical annular space 11, through which air flows upwardly from the openings 2. Upon reaching the top of cone 4 the heated air ascends through the middle of the pipe and is mixed with the hot gases that have ascended through the pipe and have been delivered through cone 8. Between cone 8 and the wall of pipe 1 is formed an annular chamber 12 that is normally filled with gases that are not subject to violent circulation. Consequently the

space 12 comprises a heat-retarding chamber, the function of which is to reduce the escape of heat from the wall of cone 8 to the shell of pipe 1 and, therefore, the air of 5 the annular space 11 absorbs and retains the heat that is transferred to it from the walls of the hot gas-conducting cone 4.

The upper end 13 of cone 8 is flanged inwardly, as shown in Fig. 1, the diameter of 10 the resultant opening being about equal to the diameter of the upper end of cone 4.

Soot or other substances that drop down through the stove pipe from above are prevented from escaping through the openings 15 2 and thus getting into the apartment because the seam formed by bead 9 and groove 10 prevents the soot from dropping down through space 12 and the inwardly projecting flanges 13 assure that any soot that 20 drops through cone 8 will pass on down through cone 4 and pipe 1.

If desired, the band 6 can be enclosed by an annular hollow casing 14 mounted on pipe 1 and the casing may be connected to 25 a suitable ventilating hood 15 by means of a conductor pipe 16. This hood arrangement is convenient in connection with my improvement when the device is used for removing gas and odors from the top of a 30 cooking range, or for any similar purpose.

Having thus described my invention, what I claim and desire to secure by Letters Patent is:

1. The combination with a stove pipe damper having a conical member open at both ends and secured at its larger end to the interior of the stove pipe and having an air inlet damper located above said large end, a second similar cone secured within said pipe above said damper and enclosing a conical annular chamber communicating with said damper, the upper end of said second cone projecting above said first mentioned cone and formed with a curved inwardly directed flange. 45

2. The combination with a stove pipe damper having a conical member open at both ends and secured at its larger end to the interior of the stove pipe and having an air inlet damper located above said large end, of a second similar cone secured within said pipe above said damper and enclosing a conical annular chamber communicating with said damper, the upper end of said second cone projecting above said first mentioned cone and forming a central gas and air mixing chamber enclosed within said pipe. 50 55

In testimony whereof I affix my signature.
BRUNO MARTIN.
